UNITED STATES PATENT OFFICE.

JAMES M. BROWN, OF PITTSBURGH, PENNSYLVANIA, ASSIGNOR TO WESTINGHOUSE ELECTRIC & MANUFACTURING COMPANY, A CORPORATION OF PENNSYLVANIA.

SWITCH.

1,332,025.

Specification of Letters Patent. Patented Feb. 24, 1920.

Application filed November 19, 1917. Serial No. 202,843.

To all whom it may concern:

Be it known that I, JAMES M. BROWN, a citizen of the United States, and a resident of Pittsburgh, in the county of Allegheny and State of Pennsylvania, have invented a new and useful Improvement in Switches, of which the following is a specification.

My invention relates to switches and particularly to switches of the drum type.

10 The object of my invention is to provide a switch of the above-indicated character that shall be simple in construction, efficient in operation and that shall occupy a minimum amount of space.

15 In practising my invention, I provide, in a switch of the drum type, a cylindrical casing for the same that is eccentrically disposed with respect to the drum shaft, thereby permitting the use of a relatively smaller cylinder than would otherwise be possible.

20 Figure 1 of the accompanying drawings is a side view, partially in section and partially in elevation, of a switch embodying my invention, and Fig. 2 is a plan view of 25 the same with the mounting panel and operating handle removed.

A switch 1, for mounting on a switch-board panel 2 or other suitable structure, comprises a shaft 3 having an actuating handle 6 at one end and an enlarged insulated portion 4 upon which contact members 5 are mounted. A cylindrical casing 7 is eccentrically disposed with respect to the shaft 3 and comprises a relatively large segment 8, a relatively small segment 9 and two circular flanged end members 10 and 11 to which the cylinder is rigidly secured by screws 17. The casing 7 is secured to one side of the panel 2 by means of bolts 12 that extend from the end member 10, through an opening 13 in the panel, to a plate 14 on the opposite side of the same. The casing 7 is conveniently formed by cutting an initially homogeneous cylinder, preferably of 45 micarta or other insulating material, longitudinally to provide a rigid and durable structure. By reason of the eccentric positioning of the shaft 3 in the casing 7, a relatively large space 15 is provided in the cylinder and on one side of the shaft for the reception of stationary contact members 16 that are secured to the segment 8 and are adapted to engage the contact members 5. It can readily be seen that, while a certain 55 radial distance is necessary at the point on

the casing 7 at which the stationary contact members 16 are mounted, it is only necessary to have a sufficient space diametrically opposite this point and between the casing wall and the shaft to permit of the turning of the contact members 5, a switch structure being thus provided that minimizes both material and space.

The segment 8 is made of greater peripheral width than the segment 9 to provide a substantial supporting means for the contact members 16, its greater peripheral engagement of the end members 10 and 11, together with two sets of the screws 17, further lending rigidity. The segment 9, acting as a cover plate, is held in position by one set of the screws 17, removal of which permits a ready inspection of the switch parts.

While I have shown and described a particular form of my invention, it is to be understood that changes may be made therein without departing from the spirit and scope of the same, as set forth in the appended claims.

I claim as my invention:

1. In a switch, the combination with co-operating movable and stationary contact members, of a cylindrical casing comprising side-wall members, the main body portions 85 of which are of different peripheral widths.

2. In a switch, the combination with co-operating movable and stationary contact members, of a cylindrical casing comprising two segments of different widths the greater 90 of which provides support for the stationary contact members.

3. A switch casing comprising two longitudinal side portions occupying different widths on the outer transverse perimeter of 95 the casing, means for supporting the same, and a switch member supported on one of said portions.

4. A switch comprising a cylindrical casing having its side walls divided into two 100 portions of different peripheral widths, a longitudinally disposed eccentric shaft in the casing and adjacent the smaller wall portion, contact members mounted on the shaft and contact members on the larger wall portion for engaging the contact members on the shaft.

5. In a switch, the combination with a movable shaft having contact members thereon, of a cylindrical casing parallel to 110

the shaft and having its side walls divided into portions of different peripheral widths and stationary contact members disposed on one of said portions.

5. 6. In a switch, the combination with a movable shaft having a contact member thereon, and a stationary coöperating contact member therefor, of a cylindrical cas-

ing of minimum diameter closely disposed in parallel and eccentric relation with respect to the shaft to provide a minimum total transverse area occupied by said contact members and said casing. 10

In testimony whereof I have hereunto subscribed my name this 29th day of Oct. 1917. 15

JAMES M. BROWN.
